DESIGN FOR A TOY PISTOL

Peter Lim, Los Angeles, Calif.

Application June 30, 1947, Serial No. 140,015

Term of patent 3½ years

(Cl. D34—15)

To all whom it may concern:

Be it known that I, Peter Lim, a citizen of the United States of America, residing at Los Angeles, in the county of Los Angeles and State of California, have invented a new, original, and ornamental Design for Toy Pistol, of which the following is a specification, reference being had to the accompanying drawing, forming part thereof.

Figure 1 is a plan view of a toy pistol, showing my new design; Figure 2 is a side view of the toy pistol; Figure 3 is a front end view of the toy pistol; and Figure 4 is a rear end view of same.

I claim:

The ornamental design for a toy pistol, as shown.

PETER LIM.
